SECTIONAL VERTICAL ACTING DOOR

Herbert C. Blodgett, Hartford City, Ind., assignor
to Overhead Door Corporation, Hartford City,
Ind.

Application September 19, 1947, Serial No. 775,023

4 Claims. (Cl. 160—229)

1

This invention relates to improvements in vertically acting door construction.

The principal objects of this invention are:

First, to provide a door structure of the horizontally hinged sectional type arranged to be opened by vertical movement of the door in which the several sections of the door may be assembled from a minimum number of different stamped or bent or rolled parts or elements, thus reducing the cost of dies and other machinery for producing the elements.

Second, to provide a structure for the sections of a horizontally hinged sectional door in which the elements of the door section may be economically produced from sheet metal by stamping or bending sheet stock and cutting the elements to the desired lengths.

Third, to provide a door of the horizontally hinged sectional type which will have a smooth exterior surface of pleasing appearance and one in which the joints are effective in excluding wind and water.

Fourth, to provide a door construction for the sections of a horizontally hinged sectional door which permits the easy and inexpensive welding of the several elements of each section and in which the size of the several elements may be readily changed to provide door sections of different sizes with a minimum of alteration or adjustment of the machinery for producing the elements.

Fifth, to provide a stile element for the ends or center of a sectional door which may be economically produced in varying lengths and easily assembled by welding to the rail and panel portions of the door section.

Sixth, to provide a combined panel and rail element for a sectional door which may be easily produced by bending or stamping from sheet metal stock to provide an overlap between the door sections and which is easily joined by welding to the stile elements of the door section.

Seventh, to provide a structure for the sections of a horizontally hinged sectional door in which none of the screws or bolts for attaching the hinge elements and fixtures of the door project through the front surface of the door to mar the smooth outer surface of the door.

Other objects and advantages pertaining to the details and economies of the invention will be apparent from a consideration of the following description and claims.

The drawings of which there are two sheets, illustrate a preferred form of my door construction.

Fig. 1 is an elevational view of the inside of my door in assembled and lowered or closed position.

Fig. 2 is a fragmentary cross sectional view along the line 2—2 in Fig. 1.

Fig. 3 is a fragmentary cross sectional view along the line 3—3 in Fig. 1.

Fig. 4 is an end elevational view of my door in installed and closed position in the doorway of a building, portions of the building structure being shown in cross section.

Fig. 5 is a fragmentary cross sectional view along the line 5—5 in Fig. 1.

Fig. 6 is a cross sectional view along line 6—6 in Fig. 1.

Fig. 7 is a fragmentary exploded perspective view of part of the elements of my door section.

While my door construction may be used on any type of conventional door, it is particularly adapted for use on large garage doors of the type which are opened by moving the door upwardly into a horizontal position. Fig. 4 illustrates an installation of this type in which a door opening between the door frame members 1 is closed by my door generally indicated at 2. The door comprises a plurality of horizontally arranged sections 3 which are joined by hinges 4 positioned at the ends of the door sections and central hinges 5 positioned between the ends of the door sections. It will be readily understood that as many central hinges 5 as are desired may be provided, depending upon the width of the door.

The outer hinges 4 are provided with rollers 6 arranged to roll in the guide rails 7, the guide rails 7 having a generally vertical reach along the sides of the door opening secured to the door frame by the brackets 8 (see Fig. 5) and a generally horizontal reach 9 extending to the rear of the door opening. The vertical and horizontal reaches of the guide rails are connected by a curved section 10. The construction and arrangement of the hinge members, rollers and guide rails will be described in greater detail presently.

Brackets 11 are secured to the wall of the building and to the upper portions of the guide rails for supporting pulleys 12 above each edge of the door and lift chains 13 are passed over the pulleys to the lower corners of the door for raising the door. The chains 13 extend to any desired type of counter balance system, the type illustrated consisting of a movable pulley 14 being connected to the end of the tension spring 15. The brackets 11 may be shaped to support

a driving motor and gears for power operation of the door, but in the example illustrated, this mechanism is omitted and the door is arranged for manual operation only.

The construction of the several sections 3 of the door is most clearly illustrated in Figs. 2, 3, 5 and 7. Each section consists of end stile elements 16, top rail element 17, bottom rail element 18, and a panel 19. The rail elements 17 and 18 are formed as by rolling or stamping the edges of sheet metal stock which also forms the panel 19.

The upper rail portion of each section as is most clearly shown in Figs. 2 and 7 consists of a horizontal flange 20 connected to the body of the panel 19, by the upwardly and outwardly opening angular rebate 21. The lower rail portion 18 of each section consists of a rearwardly turned horizontal flange 22, the rear edge of which is connected to a rearwardly and downwardly opening angular rebate portion 23. The rebate portions 21 and 23 are of equal vertical depth and extend over one half the depth of the rail sections so as to form an over-lapping joint between the sections when two sections are hinged together as shown in Fig. 2.

The end stile elements of each section as is most clearly shown in Figs. 5 and 7 consists of generally U-shaped stampings having a relatively wide inner flange 24 and a relatively narrow outer flange 25. The upper ends of the web portion of the stile elements 16 are notched on the outer side as at 26 so as to fit snugly against the rebate portion 21 of the upper rail portion of each panel. The lower ends of the stile elements 16 are notched as at 27 on their interior sides so as to fit snugly within the rebate portions 23 of the lower rail portions of each panel section. The stile elements 16 are thus conveniently and securely fastened to the panels 19 by lapping the outer flange 25 of the stile elements against the inside of the panels 19 and tack-welding the edge of the flange 25 to the panel as indicated at 28 in Figs. 2, 3 and 5. The abutting edges of the ends of the stile element and the rail portions of the panel 19 are conveniently exposed and may be welded as indicated at 29 in Fig. 5.

The stile elements 16 may also be used as interior stile elements of the door sections, but I prefer to use a slightly modified interior stile element 30, such as is illustrated in Figs. 1 and 7. The inner stile element 30 is provided with a relatively narrow outer flange 31 and a relatively wide inner flange 32 connected by the web portion 33 of the same width as the web portion of the stile elements 16. The ends of the interior stile elements 30 are notched in the same manner as the ends of the end stile elements, but instead of being formed into U-shaped cross section, the flanges 31 and 32 are folded into opposite directions from the web to form a generally Z-shaped cross section. By turning the interior flange 31 oppositely from the outer flange 32, the junction between the outer flange and the panel 19 is clearly exposed along the inside of the panel so that it may be welded thereto as indicated at 34 in Fig. 1.

The hinges 4 and 5 for joining the several sections of the door are conveniently secured to the inside flanges 24 and 32 of the stile elements by bolts 35 so that no bolts or screws project through the panels 19 to mar or interrupt the smooth outer surface of the door.

One or more of the panel sections 19 may be formed with an aperture closed with a pane of

glass 37 to form windows in the door as desired. The window panes are conveniently mounted in their openings 36 by means of annular gaskets 38 as is most clearly shown in Fig. 6.

5 The rebate portion 23 along the lower edge of the lowermost door sections forms a convenient shoulder for attaching a deformable rubber bumper 39 along the lower edge of the door as is most clearly shown in Fig. 3. The bumper may 10 be easily attached by passing self-tapping screws 40 through a flange on the bumper and the vertical wall of the rebate portion 23. Cleats 41 are secured to the center stile element of the lowermost section of the door to assist in opening and closing the door as is illustrated in Fig. 3.

15 The hinges 4 comprise upper leaves 42 secured to the inner flanges 24 of the stiles by the bolts 35 and having lower end portions bent inwardly of the door into cylindrical portions 43 receiving the hinge pins 44. The hinge pins 44 are supported between the side flanges 45 of the generally U-shaped lower hinge leaves 46. The flanges 45 also support pintle pins 47 for supporting the 20 rollers 6. The interior hinges 5 are similar to the end hinges 4 but do not have the pintle pins or rollers mounted thereon.

25 My door construction is particularly useful and economical to construct in that the combined panel and rail portions of each section of the door may be produced from sheet metal by stamping or rolling and cut to the desired length to fit door openings of various widths. The stile elements are economically produced as stampings 30 and easily welded to the panel and rail sections as previously described. The hinges and other door fixtures are easily mounted on the door sections with bolts positioned entirely on the inside of the panels so that the outer surface of the 35 finished door is completely smooth and/or attractive appearance.

40 Having thus described my invention, what I claim as new and desire to secure by Letters Patent, is:

45 1. Door construction for the sections of a horizontally hinged sectional door comprising end and intermediate stile elements of sheet metal material having narrow outer flanges and wide inner flanges connected by web sections, the upper ends of said stile elements being notched 50 from the outside, the lower ends of said stile elements being notched from the inside, said notches extending over one half the thickness of said stile elements, an outer panel of folded sheet metal construction having a flat body lapped upon the outer flanges of said stile elements and terminating in an upper rail flange lapped upon the upper ends of said stile elements, said upper rail having an outwardly opening rebate nesting within said upper notches in said stile elements, a lower rail terminal flange folded from said panel and having an inwardly opening rebate nesting within said lower notches in said stile elements, said panel being welded to said outer flanges of said stile elements with the web sections of the end stile elements flush with the end edges of the panel, and fixtures for connecting 55 said door sections to adjacent sections of the door secured thereto by bolts passed through said inner flanges of said stile elements, the abutting portions of said rail and stile elements being welded together.

60 2. Door construction for the sections of a horizontally hinged sectional door comprising end and intermediate stile elements of sheet metal

material and having outer flanges and inner flanges connected by web sections, the upper ends of said stile elements being notched from the outside, the lower ends of said stile elements being notched from the inside, a flat outer sheet metal panel lapped upon the outer flanges of said stile elements and terminating in an upper rail flange folded and lapped upon the upper ends of said stile elements, said upper rail having an outwardly opening rebate nesting within said upper notches in said stile elements, and a lower rail terminal flange folded from said panel and having an inwardly opening rebate nesting within said lower notches in said stile elements, said panel being welded to said outer flanges of said stile elements with the web sections of the end stile elements flush with the end edges of the panel.

3. Door construction for the sections of a horizontally hinged sectional door comprising end and intermediate stile elements of sheet metal material and U shaped cross section having narrow outer flanges and wide inner flanges, the upper ends of said stile elements being notched from the outside, the lower ends of said stile elements being notched from the inside, said notches extending over one-half the thickness of said stile elements, and a flat metal door panel welded in lapped engagement with said outer flanges of said stile elements and with its ends in flush arrangement with the outer edges of said end stile elements, the end stile elements being disposed in laterally inwardly opening relation whereby the webs thereof are flush with the ends of said panel, said panel terminating in upper and lower 35 terminal flanges forming rebated rail portions

folded therefrom and nesting within the notches in said stile elements and welded to the edges thereof.

4. Door construction for the sections of a horizontally hinged sectional door comprising end and intermediate stile elements of sheet metal material having narrow outer flanges and inside inner flanges, said flanges being connected by web portions disposed vertically and transversely to the 10 plane of the door section and exposed on both sides from the inside of the door, the upper ends of said stile elements being notched from the outside, the lower ends of said stile elements being notched from the inside, said intermediate stile element having the flanges thereof turned oppositely from its web portion and a flat metal door panel welded in lapped engagement with said outer flanges of said stile elements, said panel terminating in upper and lower terminal 20 flanges forming rail portions folded therefrom and nesting within said notches in said stile elements.
